LOOM CONTROL

Lothar A. Ederer, Chicago, Ill., assignor to R. J. Ederer Company, Chicago, Ill., a corporation of Illinois

Application January 21, 1931, Serial No. 510,133.

17 Claims. (Cl. 96—19)

This invention relates to a loom control. It has for one object to provide in connection with a machine for knitting or weaving or otherwise forming any sort of fabric from strands of material, means for stopping the machine automatically upon the breaking of a strand of material. Another object is to provide in connection with such an automatic stop, means for stopping the machine in a predetermined position, irrespective of the time of occurrence of the break. Another object is to provide in connection with such a machine and such an automatic stop, positive means for stopping the machine after the occurrence of a break in the most advantageous position of the parts for repair.

My invention is shown in connection with a machine for making nets. The net making construction is not illustrated in full detail as its details form no particular part of the present invention. The invention might equally well be applied to a loom, to a spinning machine and, in fact, to any machine using strands of material to form a fabric of any sort.

Other objects will appear from time to time in the specification and claims.

My invention is illustrated more or less diagrammatically in the accompanying drawings, wherein—

Figure 1 is an end elevation of a net making machine;

Figure 2 is a fragmentary front elevation, with parts broken away and parts omitted;

Figure 3 is a fragmentary side elevation, showing one of the controlling cams which is driven in phase with the power shaft;

Figure 4 is a fragmentary plan view of one end of the machine;

Figure 5 is a transverse vertical fragmentary cross section taken at line 5—5 of Figure 2 on an enlarged scale, with parts broken away;

Figure 6 is a fragmentary front elevation of the structural details shown in Figure 5, with parts omitted;

Figure 7 is a longitudinal vertical fragmentary cross section, taken at line 7—7 of Figure 1, on an enlarged scale and with parts broken away;

Figure 8 is a transverse vertical cross section taken at line 8—8 of Figure 7;

Figure 9 is a side elevation of a thread contacting lever;

Figure 10 is a plan view of the same; and

Figure 11 is a wiring diagram of the device as a whole.

Like parts are designated by like characters throughout the specification and drawings.

The invention is shown as applied to a net making machine. The parts of that machine will be described only sufficiently to indicate the application of the invention to a net making machine. The details of the machine form no particular part of the present invention.

End frame members A₁ of any suitable design, are provided and they support the mechanism. They are attached by longitudinal frame parts, designated generally by the letter A¹. Some of these parts serve the added function of supporting directly parts of the mechanism. A² is a trough, preferably at the front of the machine within which the operator may keep repair parts, spools and other necessary things. The frame in general is provided with a sufficient number of longitudinal vertical and cross frame members to support and position all of the parts which are necessary to the operation of the machine itself and to the stopping and controlling mechanism.

I shall now describe so much of the net forming mechanism as is necessary to make plain the nature and operation of the automatic stopping mechanism. The machine in the form illustrated herewith makes nets from two sets of threads, one set of threads is supplied by spools and another set of threads is supplied by shuttles. Spools B are carried on rods B¹ which are themselves carried on frame members B², suitably supported upon any sort of bracket or other structural member. The spools are preferably arranged in rows, as indicated in Figures 1 and 2. Suitably supported in brackets and extending longitudinally along the machine and above the spools is a spacer bar B³ having perforations B⁴, one for each thread or cord B⁵, as shown generally in Figure 1 and in detail in Figure 5. Above and generally parallel with the member B³ is a pair of rods B⁶. Generally parallel with each other and with the members B⁴ and B⁶ and above them, is a pair of spacing bars B⁷, B⁸, perforated as at B⁹, B¹⁰, respectively. It will be noticed, as indicated particularly in Figure 6, that the perforations B⁹, B¹⁰ are arranged with respect to each other in such manner that the thread B⁵ is run diagonally from one member B⁷ to the other member B⁸. The perforated guiding members and the associated parts are designed to guide the thread or cord and to put it under tension. B¹¹ is a longitudinal member suitably supported in brackets or other parts, and carrying a plurality of thread engaging and tensioning devices. These devices include relatively flat parts B¹² and relatively bent or inclined members B¹³, one being situated adjacent each of

the members B^{12} . The members B^{13} are bent as shown and provided with angularly disposed ends B^{14} , in which are formed perforations B^{15} . The threads or cords pass through the perforations B^{15} and between the members B^{12} , B^{13} . These two parts are so spaced with relation to each other that they exert some friction upon the thread as it moves between them. A further thread guiding part B^{16} is positioned adjacent 10 and above each pair of members B^{12} , B^{13} . The part B^{16} is notched as at B^{17} to receive the thread and has positioned upon it a bifurcated bracket member B^{18} which is provided at its upper end with a laterally bent perforated portion B^{19} . 15 Fastened to the member B^{18} is an upwardly extending bracket member B^{20} in which is pivoted a lever arm B^{21} , which is shaped as indicated in Figure 5 and provided with a downwardly facing portion in which is formed a perforation B^{22} . At its lower end the portion B^{21} has preferably a contact point B^{23} . The thread B^5 passes through the perforation B^{22} , thence over an upwardly extending elongated member B^{24} and about a roller B^{25} , which is held in position in 20 upwardly extending and downwardly facing stirrups or brackets B^{26} . B^{27} is a guiding member provided with perforations B^{28} , through which the threads pass on their way to the weaving or knitting mechanism. B^{29} is a contact bar, running 25 substantially throughout the length of the machine and of such length and so situated that each of the members B^{21} may contact it when such members have moved into the dotted line position shown in Figure 5. B^{30} is an insulation 30 for the contact bar B^{29} .

I shall now describe the mechanism for supplying and moving another set of threads, namely, the shuttles, and while these are indicated generally in Figures 1 and 2, they are shown in 40 more detail in Figures 4, 7 and 8. In Figure 4 is shown in plan a portion of the shuttle operating mechanism. C , C are bed portions upon which the shuttles move. At each side of the machine is mounted a bar C^1 which is cut along 45 its inner face to provide openings or cut away portions C^2 , separated by fingers C^3 . C^4 is a rocking lever, pivoted as at C^5 upon any suitable support. C^6 is a link connecting one end of the lever to the bar C^1 . There will ordinarily be several 50 of such lever and link assemblies connected to the bar C^1 to move it. A driving link C^7 is connected to the lever C^4 and is mounted to be reciprocated back and forth and thus to rock the lever C^4 and move the bar C^1 back and forth 55 across the machine. Mounted upon the bar C^1 is a hook bar C^8 upon which are mounted a plurality of laterally bent hooks C^9 . These hooks might be formed integrally with the bar or formed separately and attached to it. The bar C^8 is so mounted upon the bar C^1 that moves forward and back across the machine with it. At its end the bar C^8 carries a guide C^{10} which may or may not have an anti-friction roller mounted 60 upon it and which projects within a slot C^{11} in a fixed guiding member C^{12} . A portion of the slot C^{11} , as at C^{13} , is displaced sideways and thus, as the bar C^1 moves forward toward the center of the machine, carrying with it the bar C^8 , when the roller C^{10} moves into the portion C^{13} of the slot 65 C^{11} , the bar C^8 with the hooks upon it is moved laterally along the machine. Projecting upwardly and forwardly from the bar C^1 is a series of bracket members C^{14} . These brackets are joined by a longitudinal member C^{15} which runs 70 along the machine and which carries on its face 75

a contact member C^{16} , adapted to contact with the shuttles. The opposite shuttle bar C^1 and its associated parts, including, of course, the hook bar, are the same in construction as the one described above. The driving and guiding mechanism by means of which the bars are moved forward and back and guided in their motion, are essentially the same although they differ in detail from the driving linkage above described. Since these details are typical of machines of this class and 10 form no particular part of the present invention, they will not be further described. 15

D is a longitudinal frame member running generally along the machine and situated above the shuttles and shuttle moving mechanisms. At its forward edge, as viewed in Figure 2, and on its left side, as viewed in Figure 8, it is provided with notches D^1 and with a series of outwardly projecting pointed members D^2 . As will be seen from Figure 2, the pointed members are spaced 20 between the notches D^1 . A bar D^3 is positioned adjacent the notches D^1 on the under side of the member D and is provided with similarly placed notches D^4 . Carried in suitable bearings, preferably from the member D and running approximately from end to end of the machine, at least throughout the width occupied by the shuttles, is a rod D^5 , formed of electro-conductive material and carrying an insulated contact strip or bar D^6 . The rod D^5 is supported in insulated 25 bearings D^7 , one of which is shown in Figure 4, and is provided with electrical connections such as that shown in Fig. 4 at D^8 . At some point along the bar D^5 and preferably adjacent one end, is a split lever D^9 . One portion of the lever is downwardly curved or turned, as at D^{10} , and the other portion D^{11} is laterally bent away from the portion D^{10} as shown in Figure 8. Positioned upon the member C^1 is an upwardly extending bracket D^{12} which may be double or bifurcated and which carries an insulating contact member D^{15} which is positioned to be contacted by the member D^{10} or the member D^{11} . When the bar C^1 is in the right hand position, as indicated in Figure 8, the portion D^{10} of the lever D^9 is in contact with the insulated contact portion D^{15} . When the bar C^1 is moved to the dotted line position as shown in Figure 8, the contact member D^{15} moves out of contact with the lever part D^{10} and into contact with the lever part D^{11} and thus moves the lever to the dotted line position shown in that figure, and the rod D^5 is thus rotated. 30 35 40 45 50 55 60 65 70 75

E is a thread or cord contacting lever. One of these levers is used for each of the series of threads which are fed from the shuttles. The levers are formed preferably with laterally and downwardly bent portions E^1 at one end and with a downwardly bent, rounded portion E^2 at the other end and with a contact point E^3 formed in the downwardly bent portion. A yoke-like member E^4 is positioned in the lever and serves as a bearing. A pin E^5 is removably positioned in the yoke E^4 to hold the lever in position. The lever is shown mounted particularly in Figure 8. While the levers may be pivotally supported from the member D in any suitable manner, they are shown as supported on a bearing rod E^6 which is carried from the member D in suitable supporting parts E^7 . 60 65 70 75

F are shuttles, each of which is provided with a relatively flat bottom portion having raised forward ends F^1 and inclined sides F^2 which may be contacted by the contact parts C^{16} when pushed in one direction and engaged by the hooks C^9 when moved in the reverse direction. 70 75

A spool F^3 is mounted for rotation within the shuttle. Upon the spool is carried a thread F^4 which passes off as indicated particularly in Figure 8, preferably over the top of the spool F^3 about a tensioning member or rod F^5 ; is looped about a second tensioning member F^6 and passes outwardly through a perforation F^7 in the upper end or top of the shuttle frame member. There is a lever E for each of the threads or cords F^4 .

I shall now describe the knitting or weaving mechanism. As above mentioned, the net machine which is shown in the drawings forms nets of two series of twine and the net is indicated as G . It passes over a roller H , between it and a second roller H^1 , over it and between it and a third roller H^2 . It is discharged from that roller and passes over a final roller H^4 and is discharged from the machine. The rollers are all driven in phase with each other, the shaft of the roller H^1 carrying a sprocket H^8 , the shaft of the rollers H^4 carrying a sprocket H^6 , the two sprockets being connected by a chain H^7 . The shafts of each of the rollers H , H^1 and H^2 carry, respectively, gears H^8 , H^9 and H^{10} , which mesh with each other as indicated particularly in Figure 2. The driving mechanism and the power mechanism generally for operating the net making machine are not shown. They form no particular part of the present invention. It is sufficient that some means is provided for driving the necessary parts of the machine. Certain of the knitting or weaving operations are controlled by rotary cams. These cams are driven in phase with the machine. One of them, I , is indicated in Figure 3. It is mounted on a shaft I^1 , carried at any suitable place in the assembly, and it is driven at such speed that it makes one complete revolution for each reciprocation of the shuttles. It thus makes half of a revolution for each movement of the shuttle from one side of the machine to the other. As shown in Figure 3, the cam I carries a contact I^2 . The contact member I^2 is in contact with two spring contacts I^3 which are connected by electrical conductors to the shuttle contact bar D^5 . Since the shuttle contact bar D^5 is connected to the lower twine contact bar B^{29} , the contact of the member I^2 with the members I^3 effects a connection to both of the contact bars. Positioned at the other side of the cam I , that is to say, 180° separated from the contacts I^3 , is a pair of contacts I^4 .

The wiring of the machine, including the wiring of the power circuit by means of which the machine is operated, and the wiring of the secondary or control circuit, by means of which its operation is controlled, are shown in Figure 11. The main power supply is furnished by conductors J , J^1 . A magnetic clutch is indicated as at J^2 . When this clutch is energized and when the power is on, the machine will operate. If the clutch is de-energized, it will disconnect the machine and even though the motor may continue to operate, the machine will not be operative. Ordinarily in machines of this class, the friction involved is such that once the drive is disconnected or the power is turned off, the machine will stop practically instantly. For the sake of convenience, the wire J^1 is indicated as positive and the wire J as negative. J^3 is a switch by means of which wires J , J^1 may be connected to leads J^4 , J^5 , respectively. The wire J^4 is connected to a switch J^6 from which a wire J^7 leads to the negative pole of the magnetic clutch. From the positive pole of the clutch a wire J^8 leads to the switch J^6 to which switch the wire J^5 is con-

nected. A coil J^9 is inserted between the wires J^7 and J^8 to prevent sparking from the magnetic clutch. J^{10} is a switch generally similar to the switch J^6 . J^{11} is a switch operating arm connected to both of the switches and adapted to be moved to operate them. The arm J^{11} may be moved by a solenoid J^{12} . A connection J^{13} runs from the connection J^4 to the solenoid. The other end of the solenoid is connected by a connection J^{14} to the switch J^{10} and also by a connection J^{15} the same end of the solenoid is connected to a switch J^{16} . A connection J^{17} runs from the connection J^5 to one of the contacts I^4 . The other contact I^4 is connected by a connection J^{18} to the switch J^{16} . J^{19} is a resistance inserted in the circuit of the solenoid J^{12} to prevent sparking. J^{20} is a wire leading from switch J^3 to switch J^{10} . I have spoken of the switches J^3 , J^6 , J^{10} and J^{16} in the singular. From the drawings it is clear that each of the switches is a double switch.

A secondary source of current is furnished by means of wires K , K^1 , which are indicated in Figure 11 as being respectively, the minus and plus connections of a 48 volt current source. The wire K is connected to the switch J^{10} and the wire K^1 , through one or more resistances K^2 , is connected to the switch J^{16} . From the switch J^{10} a wire K^3 which is also connected to the wire K^1 , runs to one of the contact members I^3 . From the opposite contact member I^3 a wire K^4 runs to the shuttle contact bar D^5 . A wire K^5 which is connected to the wire K^4 runs to the lower twine contact bar B^{29} . Connected to the wire K is a wire K^6 which at its opposite end is connected to one end of a solenoid K^7 . The other end of the solenoid has connected to it a wire K^8 which is grounded as at K^9 and is also connected to the switch J^{16} . A resistance K^{10} is inserted in the circuit of the solenoid K^7 to prevent sparking.

The shuttle contacts L are connected to a single connection member L^1 which is grounded as at L^2 .

The lower twine contacts M are connected preferably to a single contact member M^1 which is grounded as at M^2 . These two contact members are grounded on the machine as is also the ground connection K^9 of the wire K^8 . Thus each of the grounds L^2 and M^2 may be in circuit with the ground K^9 .

It will be realized that whereas I have herewith shown and described a practical operative device, nevertheless many changes might be made in the size, shape, number and disposition of parts without departing from the spirit of my invention and I wish, therefore, that my showing be taken as in a sense diagrammatic. In particular the automatic stop arrangement which is embodied in this application might be applied to any sort of knitting or weaving machine in which any sort of fabric is made from threads, cords, yarn, twine or the like. Where in the specification and claims the words "twine", "cord", "threads" or similar words are used, they are used to mean any such member, whether it be weak or strong, formed of single strands of material or of many strands of material.

The use and operation of my invention are as follows:

For ordinary purposes, when the invention is applied to the type of machine illustrated here-with, the machine will operate continuously until a breakage occurs. If any thread, cord or twine breaks, the machine will be automatically stopped but it will stop automatically, however, at the first convenient repair point in its cycle after the

break occurs. Thus in a device where shuttles are used, the machine is arranged to stop, not immediately upon the occurrence of a breakage, but as soon thereafter as the shuttle has reached 5 a convenient position for repair. Since this automatic stopping in the form of the invention illustrated herewith is electrically operated, the operation of this feature will be described in connection with the wiring diagram shown in Figure 11.

As shown in Figure 11, the main current supply is broken, the magnetic clutch is not energized and the machine is not in operation. To commence operation, the switch J^3 is closed, which 15 puts current through the wire J^5 to the switch J^6 through the wire J^8 to the magnetic clutch, through the clutch, through the wire J^7 , the switch J^6 , the wire J^4 . When the clutch is thus energized it engages and if the driving mechanism is set in operation, the machine will be 20 operated. So long as no breakage of twine or thread occurs, the parts will undergo no change. If a breakage occurs in either of the sets of twine, that is either in one of the lower twines or one of 25 the shuttle twines, a shuttle contact or a lower twine contact will fall either upon the contact bar D^5 or the bar B^9 . The next time the contact I^2 makes contact with the members I^3 after the occurrence of such a break, current will pass from 30 the auxiliary 48 volt circuit, through the wire K^1 , through the resistance K^2 , the wire K^3 , the contact I^2 , the contact I^3 , the contact bar D^5 , one of the shuttle contacts L , through the connection L^1 to the ground L^2 , which 35 represents the machine, thence through the machine to the ground K^9 , which is also the machine, and from it to the wire K^8 , which is grounded on the machine, to the solenoid K^7 , through the wire K^6 , back to the wire K , thus completing the 40 circuit, energizing the solenoid K^7 and closing the switch J^{16} . As soon as the switch K^{16} is closed, the path of the current which energizes the solenoid K^7 is through the wire K^1 , through K^2 , to switch K^{16} , wire K^8 , solenoid K^7 , wire K^6 , wire K , back to the current source. The parts will 45 remain in this position until the contact I^2 has completed 180° of movement and makes contact with the contacts I^4 . Then current passes from wire J^1 , through the switch J^3 , wire J^5 , J^{17} , contacts I^4 , wire J^{18} , switch J^{16} , wire J^{15} , to the solenoid J^{12} , 50 from the solenoid J^{12} to wire J^{13} , to wire J^4 , back through the switch J^3 to wire J . Thus the solenoid J^{12} is energized and it moves to open the switch J^6 and close switch J^{10} . The opening of 55 the switch J^6 breaks the connection to the magnetic clutch, thus stopping the machine. The position of the contacts I^4 is such that the machine will be brought to a stop only with the shuttles at the front of the machine, that is, at 60 the opposite side from the position shown in Figures 1 and 8.

With the machine stopped as a result of the automatic action above described, current is passing from wire J^1 , through switch J^3 , through wire J^{20} , to switch J^{10} , wire J^{14} , to solenoid J^{12} , thence through wire J^{13} , J^4 , switch J^3 to wire J . Thus the solenoid is held in position to hold switch J^6 open and to hold switch J^{10} closed. When the switch J^{10} is closed, current is supplied from wire K^1 , through resistance K^2 , wire K^3 , to switch J^{10} , back along wire K to the line, thus short circuiting solenoid K^7 and permitting the opening of the switch J^{16} .

To start the machine now it is necessary, after 75 the breakage has been repaired, to open switch J^3 ,

thus de-energizing the solenoid J^{12} and permitting the opening of the switch J^{10} and the closing of the switch J^6 . Then, upon a subsequent closing of the switch J^3 , the parts are in position so that the magnetic clutch is energized and the machine may be put in operation.

I claim:

1. In combination in a machine for making fabric from strands, automatic means for stopping the machine at a predetermined point in its 10 normal cycle after the breakage of a strand, in response to said breakage, and irrespective of the time of breakage said means including members movably mounted, one for each strand, and adapted in normal operation of the machine to 15 be held in substantially immovable position by said strands, and free to move into operative position upon the breaking of a strand and thereby to initiate the action of the stopping mechanism, and means for holding some of said movably mounted members in inoperative position, irrespective of the condition of the strands, during a portion of the cycle of operation of the machine.

2. In combination in a machine for making fabric from strands, automatic means for stopping the machine at a predetermined point in its 20 normal cycle after the breakage of a strand, in response to said breakage, and irrespective of the time of breakage said means including members movably mounted, and adapted in normal operation of the machine to be held in substantially 25 immovable position by said strands, and means for holding some of said movably mounted members in inoperative position, irrespective of the condition of the strands, during a portion of the 30 cycle of operation of the machine.

3. In combination in a machine for forming fabric from thread, means for supplying thread and for forming it into a fabric, and automatic means for stopping the operation of the machine 40 upon the breaking of a thread, which includes a movably mounted member, said member held against movement by the thread and mounted to move upon breaking of the thread, and electric conductor means, mounted to be contacted by said 45 movable member when the latter is free to move, the conductor and movable member being in electric circuit and means for rendering said circuit incomplete for an appreciable time interval after breakage said stopping means including a circuit 50 making member mounted for rotation.

4. In combination in a machine for forming fabric from threads, means for supplying a plurality of threads and for forming them into a fabric, and automatic means for stopping the 55 operation of the machine upon the breaking of a thread, which includes a plurality of movably mounted members, one for each thread, said members held against movement by the threads, said members mounted to move upon breaking of the 60 thread, and electric conductor means mounted to be contacted by said movable members when the latter are free to move, the conductor and movable members being in electric circuit, a conductor and a movable member adapted, when the movable member is free to move, to contact each other to complete an electrical circuit and to initiate the operation of a stopping mechanism to stop the machine and means for rendering said circuit incomplete for an appreciable time interval after 70 breakage said stopping means including a circuit making member mounted for rotation.

5. In combination in a machine for forming fabric from threads, means for supplying a plurality of threads and for forming them into a 75

fabric, and automatic means for stopping the operation of the machine upon the breaking of a thread, which includes a plurality of movably mounted members, one for each thread, said members held against movement by the threads and mounted to move upon breaking of the thread, and electric conductor means mounted to be contacted by said movable members when the latter are free to move, the conductor and movable members being in electric circuit, a conductor and a movable member adapted, when the movable member is free to move, to contact each other to complete an electrical circuit and to initiate the operation of a stopping mechanism to stop the machine, the stopping mechanism including means to prevent the stopping of the machine until the latter has moved to a predetermined position after the occurrence of the break and including a contact member mounted for rotation.

6. In combination in a machine for making fabric from strands, said machine including parts mounted for rotation, automatic means for stopping the machine at a predetermined point after the breakage of a strand, in response to said breakage, said means including members movably mounted and adapted, in normal operation of the machine, to be held in substantially immovable position by said strands, and free to move into operative position upon the breaking of a strand and thereby to initiate the action of the stopping mechanism, said means including a contact member mounted on one of said rotatably mounted parts.

7. In combination in a machine for making fabric from strands, said machine including parts mounted for rotation, automatic means for stopping the machine at a predetermined point after the breakage of a strand, in response to said breakage, said means including members movably mounted, one for each strand, and adapted in normal operation of the machine to be held in substantially immovable position by said strands, and free to move into operative position upon the breaking of a strand and thereby to initiate the action of the stopping mechanism, said stopping means including a contact member mounted on one of said rotatably mounted parts.

8. In combination in a machine for making fabric from strands, said machine including parts mounted for rotation, automatic means for stopping the machine at a predetermined point after the breakage of a strand, in response to said breakage, said means including members movably mounted, one for each strand, and adapted, in normal operation of the machine, to be held in substantially immovable position by said strands, and free to move into operative position upon the breaking of a strand and thereby to initiate the action of the stopping mechanism, said stopping means including a contact member mounted on one of said rotatably mounted parts, and means for holding some of said movably mounted members in inoperative position, irrespective of the condition of the strands, during a portion of the cycle of operation of the machine.

9. In combination in a machine for making fabric from strands, said machine including parts mounted for rotation, automatic means for stopping the machine at a predetermined point after the breakage of a strand, in response to said breakage, said means including members movably mounted and adapted, in normal operation

of the machine, to be held in substantially immovable position by said strands, said means including a contact member mounted on one of said rotatably mounted parts.

10. In combination in a machine for making fabric from strands, said machine including parts mounted for rotation, automatic means for stopping the machine, after the breakage of a strand, said means including electric circuit forming members, means for energizing the circuit, circuit completing members normally held out of circuit by a strand and adapted to be freed for movement into circuit upon breakage of a strand, and a circuit interrupter, effective to prevent completion of the circuit after breakage of a strand until the machine has reached a suitable point in its cycle, said stopping means including a contact member mounted on one of said rotatably mounted parts.

11. In combination in a machine for making fabric from strands, said machine including parts mounted for rotation, automatic means for stopping the machine, after the breakage of a strand, said means including electric circuit forming members, means for energizing the circuit, circuit completing members normally held out of circuit by a strand and adapted to be freed for movement into circuit upon breakage of a strand, and a circuit interrupter, said stopping means including a contact member mounted on one of said rotatably mounted parts.

12. In combination in a machine for making fabric from strands, automatic means for stopping the machine after a relatively limited movement at a predetermined point in its cycle after the breakage of a strand, in response to said breakage, said means including members movably mounted and adapted in normal operation of the machine to be held in substantially immovable position by said strands, said means including a rotating contact member mounted upon a normally rotating part of the machine.

13. In combination in a machine for making fabric from strands, automatic means for stopping the machine after a relatively limited movement at a predetermined point in its cycle after the breakage of a strand, in response to said breakage, said means including members movably mounted and adapted in normal operation of the machine to be held in substantially immovable position by said strands, and free to move into operative position upon the breaking of a strand and thereby to initiate the action of the stopping mechanism, said means including a rotating contact member mounted upon a normally rotating part of the machine.

14. The combination with a fabric making machine, a stop motion mechanism therefor comprising a first electric circuit having the continuity thereof normally broken at at least two points, means responsive to breakage of a thread for closing one of said "breaks", means operable in response to operation of the machine for periodically closing another of said "breaks", a second electric circuit having the continuity thereof normally broken at a plurality of points, means responsive to the simultaneous closing of the "breaks" in the first circuit for closing one of the "breaks" in the second circuit, said periodic closing means also operating to periodically close a break in the second circuit in response to operation of the machine and means responsive to the simultaneous closing of the breaks in the second circuit for stopping the machine.

15. A stop motion mechanism for fabric mak-

ing machines comprising a plurality of electric circuits, one of said circuits in normal operation of the machine being energized and the others deenergized, said normally deenergized circuits 5 each including a plurality of normally open "breaks", means to energize one of said normally deenergized circuits including a part operable in response to operation of the machine for periodically closing one of said breaks in said circuit, and means responsive to breakage of a thread on the machine for closing another break in said circuit to complete the continuity thereof, means responsive to the energization of said normally deenergized circuit to energize another of 10 said normally deenergized circuits, said periodic closing means operating also to periodically close a break in said other circuit, to thereby complete its continuity, and means responsive to completion of the continuity of said other circuit for deenergizing the normally energized circuit, to 15 stop the machine and to restore the second mentioned normally deenergized circuit to normal deenergized condition.

16. The combination with a fabric making machine, a stop motion therefor comprising a plurality of normally deenergized electric circuits, and a normally energized electric circuit, the operation of the machine being dependent upon

continual energization of said last mentioned circuit, means for energizing one of said normally deenergized circuits in response to the breakage of a thread in the machine, means for energizing the second normally deenergized circuit in response to energization of said first named deenergized circuit, and means responsive to energization of said second mentioned normally deenergized circuit for deenergizing the normally energized circuit to stop the mechanism and to deenergize the second of said normally deenergized circuits. 5

17. The combination with a fabric making machine, a stop motion mechanism therefor, comprising a first and a second electric circuit, both 15 of said circuits including a plurality of normally open "breaks", means operable in response to operation of the machine for periodically closing a break in each of said circuits, means operable in response to breaking of a thread in the machine for closing a break in one of said circuits, means operable in response to the simultaneous closing of the breaks in said last mentioned circuit for closing another break in the other circuit, and means responsive to the simultaneous 20 closing of breaks in said other circuit for stopping the machine. 25
